US00D665774S

(12) **United States Design Patent**
Akana et al.

(10) **Patent No.:** US D665,774 S
(45) **Date of Patent:** ** Aug. 21, 2012

(54) **ELECTRONIC DEVICE**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/414,100**

(22) Filed: **Feb. 24, 2012**

Related U.S. Application Data

(60) Continuation of application No. 29/400,904, filed on Sep. 2, 2011, now Pat. No. Des. 655,688, which is a continuation of application No. 29/386,812, filed on Mar. 4, 2011, now Pat. No. Des. 644,624, which is a continuation of application No. 29/366,863, filed on Jul. 30, 2010, now Pat. No. Des. 634,297, which is a division of application No. 29/343,062, filed on Sep. 4, 2009, now Pat. No. Des. 622,696.

(57) **CLAIM**

The ornamental design for an electronic device, as shown and described.

DESCRIPTION

FIG. 1 is a bottom front perspective view of an electronic device showing our new design;

FIG. 2 is a bottom rear perspective view thereof;

FIG. 3 is front view thereof;

FIG. 4 is rear view thereof;

FIG. 5 is a top plan view thereof;

FIG. 6 is a left side view thereof;

FIG. 7 is a right side view thereof;

FIG. 8 is bottom plan view thereof;

FIG. 9 is a top rear perspective view thereof; and,

FIG. 10 is a top front perspective view thereof.

The dashed broken lines in the Figures show portions of the electronic device which form no part of the claimed design.

The dot dash lines in the Figures represent an unclaimed boundary line and form no part of the claimed design.

The shade lines in the Figures show contour and not surface ornamentation.
